ELECTRON DISCHARGE DEVICE AND THE
METHOD OF ASSEMBLY THEREOFCharles T. Goddard, New York, N. Y., assignor to
Western Electric Company, Incorporated, New
York, N. Y., a corporation of New York

Application August 4, 1942, Serial No. 453,514

24 Claims. (Cl. 250—27.5)

This invention relates to electron discharge devices and the method of assembly thereof, and more particularly to types of devices for use in high frequency transmission systems.

In the manufacture of such devices, the accurate positioning of the various elements relative to each other is of utmost importance in order that the device when complete will produce the desired results.

Objects of the invention are to provide a simple and highly efficient electron discharge device and a method of assembling the same.

With these and other objects in view, the invention comprises an electron discharge device and a method of assembling the same, the latter including steps through the aid of tools for locating and mounting a filament support with respect to a fixed part, locating a grid element thereto, adjusting the grid element through the aid of a dummy filament, and subsequently mounting the filament and other elements.

Other objects and advantages will be apparent from the following detailed description when considered in conjunction with the accompanying drawings, wherein

Fig. 1 is a side elevational view partially in section of the lower shell and leads and illustrates the mounting of the lower filament support;

Fig. 2 is a top plan view of the structure shown in Fig. 1;

Fig. 3 is an enlarged fragmentary top plan view illustrating the positioning of the grid with respect to the lower filament support;

Fig. 4 is an enlarged vertical sectional view of the lower shell structure illustrating the upper filament support mounted and the dummy filament in place;

Fig. 5 is similar to Fig. 4, illustrating the structure after the mounting of the filament;

Fig. 6 is a top plan view illustrating the mounting of the anode;

Fig. 7 is a fragmentary sectional view taken along the line 7—7 of Fig. 8, and

Fig. 8 is a front elevational view of the completed device, portions thereof being broken away.

Referring now to the drawings, attention is first directed to Fig. 1, which illustrates a lower shell 10 of the contour shown, with various leads 11, 12, 14 and 15. This structure thus far described is preformed and is not considered as a step of the method but as a part of the complete structure. The first step of the method is the locating of a lower filament support 16. This support has a flattened end 17 in which a hole 18

is provided for the filament, the opposite end being supported by a bracket 19 of a contour adapted to be disposed upon the lead 11. The support 16 is disposed upon the lead 11 at the desired height, and through the aid of a tool 20, the end 17, particularly the hole 18 therein, is accurately located a fixed distance from the lead 12. The tool 20 has an aperture 21 therein, adjacent one end, adapted to receive the lead 12 when the tool is positioned thereon, the other end of the tool being reduced in width as shown, to provide a surface 22 adapted to be positioned in engagement with the lead 15. When the tool 20 is disposed in place, a pin 23 is lowered through an aperture 24, and the filament support 16 is adjusted arcuately about its lead 11 until the pin 23 is free to drop through the hole 18. When this has been accomplished, the support 16 may be fixed to its lead by suitable means such as welding, and the hole 18 will be fixed in its location with respect to the lead 12. This step of the method having been completed, the pin 23 and the tool 20 may be removed.

The next step includes the mounting of a grid indicated generally at 25. In the present embodiment the grid is of the fin type, including a mandrel 27 about which portions of spiral convolutions 28 of grid wire are disposed. The mandrel with the grid wire is partially embedded in a portion of a bracket 29, another portion thereof being formed to receive and conform to lead 12. The connection between the grid and its lead, at the last mentioned portion, is such that the grid will be held by friction in any desired position yet may be rotated on the lead by the application of suitable force.

All of the elements including the filament supports and the filament, the grid and the anode are mounted with respect to one object, namely the lead 12. In the previous step of the method the lower filament support 16, particularly the hole 18 therein, was accurately located by the aid of the tool 20 a given distance from the lead 12 and at a definite position with respect to the lead. The said given distance at which the hole 18 is located with respect to the lead 12 is also a given dimension of the grid 25, this dimension being the distance between the center of the free convolution portions of the grid wire and the center of the portion of the bracket which is disposed upon the lead 12. This dimension being known, the tool 20 is formed accordingly to position the center of the aperture 21 a given distance from the aperture 24 which receives the pin 23 for locating the hole 18. Thus by locating the bracket

portion of the grid upon the lead 12, it will be known that the center of the grid convolutions 28 will lie in arcuate alignment with the hole 18 or in an arc which would intersect the center of the hole 18. Thus after the grid is mounted upon its lead 12, the center of the grid convolutions may be aligned with the center of the hole 18 by arcuate adjustment of the grid. This may be made through the aid of a tool 31. The tool 31 is of a block type structure made hollow at 32, with an arcuate contour at 33 to conform to the adjacent portion of the bracket 29 and with parallel walls 34 to engage the adjacent sides of the grid bracket. Projections 35 of the tool terminating in a common plane with the center of the hole 18, when the grid is accurately positioned, serve, in this instance, to aid in the location of the grid and serve subsequently in cooperation with adjacent surfaces 37 in the mounting of the anode, as will hereinafter be described.

With the tool 31 thus positioned as shown in Fig. 3, the grid may be readily moved about its lead in either direction until it is centered with the hole 18 in the filament support. The grid is not fixed to its lead at this point in the method, but is held by its frictional engagement with the lead in its adjusted position so that a further adjustment may be made subsequently in the assembling method if such adjustment is found necessary.

Attention is now directed to Fig. 4, which illustrates an upper filament support 40 similar in structure to the forward or flattened end 17 of the support 16 and provided with a hole or aperture 41 therein. The support 40 is mounted upon the free end of a resilient hook-shaped wire 42, the opposite end being fixed to its lead 14 by suitable means such as welding. Suitable means (not shown) may be employed in locating the wire 42 adjacent the lead 14 for the welding or mounting operation. A dummy filament 44 may, if desired, be employed to locate the hole 41 in central alignment with the grid convolutions 28 and hole 18 in the lower filament support 16. This may be done during or after the mounting of the upper filament support 40. At this time an additional adjustment of the grid may be found necessary through the aid of the tool 31. This adjustment of the upper filament support with respect to the grid and lower filament support is a step important to assure accurate positioning of a filament 46 (Fig. 5) when mounted in place. During all adjustments, it will be apparent that the entire grid, the filament supports and the dummy filament 44 may be observed. The same is true during the mounting of the filament 46.

When mounting the filament 46, it is important that the wire 42 upon which the upper filament support 40 is mounted, is flexed a given distance to assure predetermined tension on the filament after it has been mounted. This may be accomplished by a tool 47. The filament 46 is then disposed in place by passing it downwardly through the hole 41, through the convolutions 28 of the grid, through the hole 18 in the lower support 16, and allowed to rest upon the surface of the shell 10. Thus the filament when first disposed in place as described, is of excess length, the excess portions being subsequently removed after the welding of the filament to its supports, these excess lengths being shown in dot and dash lines in Fig. 5. The tool 47 having hooked ends 48 and 49 adapted to extend around the lower and upper filament supports, or more

specifically the bracket 19 and the wire 42 flexed the desired distance. The filament 46 is then secured in place by suitable means such as arc welding. The tool 47 is left in place until after the welding operation and until the associated parts adjacent the welds have had time to cool. At this time the tool may be removed by sliding it in a direction to free it of the bracket 19, this being done without disturbing the wire 42 or the filament 46.

At this time during the method of assembly, another check is made on the alignment of the filament and grid. This is important due to the fact that the filament may not be in the same location after the welding as before, this being due to the possible travel of the filament during the welding operation. Furthermore, due to the application of the welds from the same direction, from the left (Fig. 5) and to the ends of the supports 16 and 40, the travel, if any, of the ends of the filament would be in the same direction. Although there is but little clearance between the filament and the walls of the holes 18 and 41, the material of the filament and its supports may flow when softened during the welding operation, and with this possibility in mind, a further checking of the grid and its location with respect to the filament is essential.

By applying the welding means at the ends 30 of the filament supports and in a direction toward the filament and the leads of the respective supports, the travel, if any, of the ends of the filament will be transverse to the general plane of the grid so that further adjustment of the grid 35 through its arcuate movement about its lead 12, may be made to again create an alignment of the center line of the grid, namely the center line of the arcuate ends of the grid convolutions, with the filament. When this has been accomplished, the grid may be secured in place on its lead by suitable means such as welding.

The next step includes the mounting of an anode, indicated at 50, which in the present embodiment is formed of two like portions abutting each other at 51, where they are secured together by punched out portions 52, other portions 53 extending arcuately away from each other to form an arc, the center of which is at the filament 46 and the center of the grid convolutions 28. Continuing with the formation of the portions of the anode, it will be observed that they extend outwardly in a common plane as at 54, their ends projecting diagonally therefrom at like angles as indicated at 55.

Beneath the portions 51 and integral therewith, are like portions 56 which extend in spaced parallel planes, as shown, adapted to be positioned upon each side of the lead 15. In actual structure the portions 56 are spaced apart a greater distance than the diameter of the lead 15 and are also of greater length than this dimension of the lead, as shown in Fig. 7, to allow for adjustment or location of the anode at various positions with respect to its lead, depending upon the final location of the grid and filament. With this structure of the anode, it may be moved in a horizontal plane (Fig. 6) into the position shown in this figure, its final position being governed by the tool 31. At this step in the method, the tool can no longer be moved arcuately about the lead 12, as the grid has been fixed to its lead. Therefore, when the anode has been disposed in the position shown, with the projections 35 positioned within the anode and the portions 54 of the latter resting against the surfaces 37

of the tool, the anode is accurately located with the center of the portion 53 thereof at the center of the filament 46 and grid convolutions 28. When in this position the portions 56 of the anode will lie upon each side of the lead 15, and while the anode is thus held in place against the tool 31, the portions 56 may be secured to the lead 15 by suitable means, such as spot welding. The tool 31 may then be removed by moving it to the left (Fig. 6), to move the opposite ends free of the anode and of the filament supports, after which it may be moved upwardly or laterally free of the grid. Finally, an upper shell 60 may be disposed upon and fused to the lower shell 10, evacuated in the usual manner, and sealed to complete the formation of the device.

In reviewing the step of the method, it will be apparent that all of the elements have been located accurately with respect to one object, namely the lead 12. During the preforming of the shell 10 with the leads therein, this structure may be presumed to have the leads disposed at accurately spaced positions, but due to the fact that the elements supported by the leads must be mounted so that the filament, the arcuate ends of the grid convolutions and the arcuate portion of the anode will have a common center, it has been found advantageous not to depend upon the accuracy in which the leads are mounted in their shell, but the mounting of the elements from a given object. It is with this thought in mind that the lower filament support or the hole 18 therein, is located a known distance from the selected object, namely the lead 12, this known distance being the distance between the mounting center and the convolution center of the grid which will locate the latter the same distance from the object or lead 12. Thus through arcuate adjustment of the grid, these centers may be aligned. Furthermore, the tool 31 with its arcuate recesses 33 formed to allow for the thickness of the bracket portion disposed upon the lead 12, performs its functions about the lead in not only adjusting the grid but in locating the anode with respect thereto. Here again the tool functions, through the aid of the projections 35 and the surfaces 37, to locate the center of the anode, namely the center of the arcuate portion 53 at the center of the filament and the grid convolutions. As a result thereof, the maximum efficiency of the elements may be obtained.

Although specific improvements of the invention have been shown and described, it will be understood that they are but illustrative and that various modifications may be made therein without departing from the scope and spirit of this invention as defined by the appended claims.

What is claimed is:

1. The method of assembling an electron discharge device having a vessel of two shell sections, one provided with spaced leads, the method comprising mounting a filament support with a filament receiving portion on its respective lead with the said portion a given distance from the lead for a grid having a grid wire formed arcuately about a center, positioning the grid on its lead, aligning the grid center with the said portion of the filament support, mounting another filament support on its lead with a filament receiving portion thereof disposed in alignment with the said center, securing a filament to the said portions, mounting an anode on its lead, and completing the device by sealing the shells together and evacuating them.

2. The method of assembling an electron dis-

charge device having a vessel of two shell sections, one provided with spaced leads, the method comprising mounting a filament support with a filament receiving portion on its respective lead with the said portion a given distance from the lead for a grid having a grid wire formed arcuately about a center, positioning the grid on its lead, adjusting the grid arcuately about its lead until the center thereof is aligned with the said portion of the filament support, mounting another filament support on its lead with a filament receiving portion thereof disposed in alignment with the said center, securing a filament to the said portions, mounting an anode on its lead, and completing the device by sealing the shells together and evacuating them.

3. The method of assembling an electron discharge device having a vessel of two shell sections, one provided with spaced leads, the method comprising mounting a filament support with a filament receiving portion on its respective lead with the said portion a given distance from the lead for a grid having a grid wire formed arcuately about a center, positioning the grid on its lead, aligning the grid center with the said portion of the filament support, mounting another filament support on its lead with a filament receiving portion thereof disposed in alignment with the said center, securing a filament to the said portions, mounting an anode, having a portion arcuate about a center, with the said center at the grid center, and completing the device by sealing the shells together and evacuating them.

4. The method of assembling an electron discharge device having a vessel of two shell sections, one provided with spaced leads, the method comprising mounting a filament support with a filament receiving portion on its respective lead with the said portion a given distance from the lead for a grid having a grid wire formed arcuately about a center, positioning the grid on its lead, aligning the grid center with the said portion of the filament support, mounting another filament support on its lead with a filament receiving portion thereof disposed in alignment with the said center, securing a filament to the said portions, mounting an anode a given distance from the grid lead, and completing the device by sealing the shells together and evacuating them.

5. The method of assembling an electron discharge device having a vessel of two sections, one provided with spaced leads, the method comprising successively locating filament supports, a grid and an anode on their respective leads and adjusting them, the filament supports, the grid and the anode, relative to a predetermined one of the leads, securing a filament to the supports, and completing the device by sealing the sections together and evacuating them.

6. The method of assembling an electron discharge device having a vessel of two sections, one provided with spaced leads, the method comprising successively locating filament supports, a grid and an anode on their respective leads and adjusting them, the filament supports, the grid and the anode, relative to a predetermined one of the leads, securing a filament to the supports prior to the locating and adjustment of the anode, and completing the device by sealing the sections together and evacuating them.

7. The method of assembling an electron discharge device having a vessel of two shell sections, one provided with spaced leads, the method comprising successively locating filament supports, a grid and an anode on their respective

leads and adjusting them relative to a predetermined one of the leads, welding a filament to the supports prior to the locating and adjustment of the anode, adjusting the grid relative to the filament to compensate for travel of the filament when being welded, and completing the device by sealing the shells together and evacuating them.

8. The method of assembling an electron discharge device having a vessel of two shell sections, one provided with spaced leads, the method comprising successively locating filament supports, a grid and an anode on their respective leads and adjusting them relative to a predetermined one of the leads, securing a filament to the supports prior to the locating and adjustment of the anode, holding one of the supports in a flexed position during welding of the filament, and completing the device by sealing the shells together and evacuating them.

9. The method of assembling an electron discharge device having a vessel of two shell sections, one provided with spaced leads, the method comprising successively locating filament supports, a grid and an anode on their respective leads and adjusting them relative to a predetermined one of the leads, employing a dummy filament between the supports during the relative adjustments of the grid and supports, securing a filament to the supports prior to the locating and adjustment of the anode, and completing the device by sealing the shells together and evacuating them.

10. An electron discharge device comprising a hollow vessel of two shell sections, one provided with spaced leads for a grid, an anode and filament supports, a filament support, having a filament receiving portion, mounted on its lead with the said portion disposed a given distance from the grid lead, a grid mounted upon its lead and having a grid wire formed arcuately about a center spaced the said given distance from the grid lead and in alignment with the said portion, another filament support, having a filament receiving portion, mounted upon its lead with its portion in alignment with the said center and other portion, a filament secured to the portions of the supports, and an anode mounted upon its lead.

11. An electron discharge device comprising a hollow vessel of two shell sections, one provided with spaced leads for a grid, an anode and filament supports, a filament support, having a filament receiving portion, mounted on its lead with the said portion disposed a given distance from the grid lead, a grid having a body, apertured for mounting on its lead, supporting a grid wire formed arcuately about a center spaced the given distances from the lead disposed with the said center in alignment with the said portion, another filament support, having a filament receiving portion, mounted upon its lead with its portion in alignment with the said center and other portion, a filament secured to the portions of the supports, and an anode mounted upon its lead.

12. An electron discharge device comprising a hollow vessel of two shell sections, one provided with spaced leads for a grid, an anode and filament supports, a filament support, having a filament receiving portion, mounted on its lead with the said portion disposed a given distance from the grid lead, a grid having a body, apertured longitudinally thereof for mounting on its lead, supporting a grid wire formed arcuately about a center spaced the given distances from the lead

disposed with the said center in alignment with the said portion, another filament support, having a filament receiving portion, mounted upon its lead with its portion in alignment with the said center and other portion, a filament secured to the portions of the supports, and an anode mounted upon its lead.

13. An electron discharge device comprising a hollow vessel of two shell sections, one provided with spaced leads for a grid, an anode and filament supports, a grid having a body, with a longitudinal aperture therein to receive its lead for pivotal adjustable mounting thereon relative to the other leads, and supporting a grid wire with convolutions formed arcuately about a center line spaced a given distance from the lead, filament supports mounted upon their leads and having filament receiving portions disposed in alignment with the said center line, a filament mounted upon the supports at the center line, and an anode mounted upon its lead.

14. An electron discharge device comprising a hollow vessel of two shell sections, one provided with spaced leads for a grid, an anode and filament supports, a filament support, having a filament receiving portion, mounted on its lead with the said portion disposed a given distance from the grid lead, a grid mounted upon its lead, having a grid wire formed arcuately about a center spaced the said given distance from the grid lead and movable arcuately about its lead to align the said center with the said portion, another filament support, having a filament receiving portion, mounted upon its lead with its portion in alignment with the said center and other portion, a filament secured to the portions of the supports, an anode having a portion formed arcuately about a center and portions adapted to straddle its lead for movement of the anode relative to its lead to position its center at the grid center, and means to secure the portions to their lead.

15. An electron discharge device comprising a hollow vessel of two shell sections, one provided with spaced leads for a grid, an anode and filament supports, a filament support, having a filament receiving portion, mounted on its lead with the said portion disposed a given distance from the grid lead, a grid mounted upon its lead, having a grid wire formed arcuately about a center spaced the said given distance from the grid lead and movable arcuately about its lead to align the said center with the said portion, another filament support, having a filament receiving portion, mounted upon its lead with its portion in alignment with the said center and other portion, a filament secured to the portions of the supports, an anode formed of connected similar sections providing portions formed arcuately about a center and other portions adapted to straddle its lead for movement into location with its center at the grid center, and means to secure the last mentioned portions together.

16. In the manufacture of an electron discharge device involving a vessel of precast shell sections, one provided with spaced leads for a grid, an anode and filament supports, the method which comprises positioning a filament support with a filament receiving portion on its respective lead, placing a locating member on the grid lead and through the aid thereof locating the said portion a given distance from the grid lead, removing the locating member, positioning a grid, having a grid wire formed arcuately about a center, on its lead, positioning a tool on the grid to move the

grid thereby and align the center thereof with the said portion, mounting a filament at the portion, locating an anode adjacent the grid by the tool, securing the anode to its lead, removing the tool and completing the device by sealing the shell sections together and evacuating them.

17. In the manufacture of an electron discharge device involving a vessel of precast sections, one provided with leads for a grid, an anode and filament supports, the method which comprises positioning a filament support with a filament receiving portion on its respective lead, placing a locating member on the grid lead and through the aid thereof locating the said portion a given distance from the grid lead, removing the locating member, positioning a grid, having a grid wire formed arcuately about a center, on its lead with the said center in alignment with the said portion, mounting another filament support, having a filament receiving portion, with its portion in alignment with the said center and other portion, mounting a filament at the portions, mounting an anode on its lead adjacent the grid, and completing the device by sealing the sections together.

18. In the manufacture of an electron discharge device involving a vessel of precast sections, one provided with leads for a grid, an anode and filament supports, the method which comprises positioning a filament support with a filament receiving portion on its respective lead with the said portion located a given distance from the grid support, positioning a grid having a body formed for pivotal mounting on its lead and to support grid wire formed arcuately about a center, positioning a tool on the grid to move the grid thereby about its lead to align the center thereof with the portion, removing the tool, mounting another filament support, having a filament receiving portion, with its portion in alignment with the said center and other portion, mounting a filament at the portions, mounting an anode on its lead adjacent the grid, and completing the device by sealing the sections together.

19. In the manufacture of an electron discharge device involving a vessel of precast sections, one provided with leads for a grid, an anode and filament supports, the method which comprises positioning a filament support with a filament receiving portion on its respective lead with the said portion located a given distance from the grid support, positioning a grid having a body formed for pivotal mounting on its lead and to support grid wire formed arcuately about a center, positioning a tool on the grid to move the grid thereby about its lead to align the center thereof with the portion, mounting another filament support, having a filament receiving portion, with its portion in alignment with the said center and other portion, locating an anode on its lead adjacent the grid by the tool, securing the anode to its lead, removing the tool, and completing the device by sealing the sections together.

20. In the manufacture of an electron discharge device involving a vessel of precast sections, one provided with leads for a grid, an anode and filament supports, the method which comprises positioning a filament support with a filament receiving portion on its respective lead with the said portion located a given distance from the grid support, positioning a grid, having a grid wire formed arcuately about a center, on its lead with the said center in alignment with the said

portion, mounting a resilient filament support having a filament receiving portion with its portion in general alignment with the said center and other portion, flexing the resilient support toward the other support to position the portions a given distance from each other, mounting a filament at the portions, mounting an anode on its lead adjacent the grid, and completing the device by sealing the sections together.

21. In the manufacture of an electron discharge device involving a vessel of precast sections, one provided with leads for a grid, an anode and filament supports, the method which comprises positioning a filament support with a filament receiving portion on its respective lead with the said portion located a given distance from the grid support, positioning a grid, having a grid wire formed arcuately about a center, on its lead with the said center in alignment with the said portion, mounting a resilient filament support having a filament receiving portion with its portion in general alignment with the said center and other portion, flexing the resilient support toward the other support to position the portions a given distance from each other, connecting the filament supports with a holding member to maintain the given distance of the portions, mounting a filament at the portions, removing the holding member, mounting an anode on its lead adjacent the grid, and completing the device by sealing the sections together.

22. In the manufacture of an electron discharge device involving a vessel of precast sections, one provided with leads for a grid, an anode and filament supports, the method which comprises positioning a filament support with a filament receiving portion on its respective lead, placing a locating member on the grid lead and through the aid thereof locating the said portion a given distance from the grid lead, removing the locating member, positioning a grid having a body formed for pivotal mounting on its lead and to support grid wire formed arcuately about a center, positioning a tool on the grid to move the grid thereby about its lead to align the center thereof with the portion, mounting another filament support, having a filament receiving portion, with its portion in alignment with the said center and other portion, removing the tool, mounting an anode on its lead adjacent the grid, and completing the device by sealing the sections together.

23. In the manufacture of an electron discharge device involving a vessel of precast sections, one provided with leads for a grid, an anode and filament supports, the method which comprises positioning a filament support with a filament receiving portion on its respective lead, placing a locating member on the grid lead and through the aid thereof locating the said portion a given distance from the grid lead, removing the locating member, positioning a grid having a body formed for pivotal mounting on its lead and to support grid wire formed arcuately about a center, positioning a tool on the grid to move the grid thereby about its lead to align the center thereof with the portion, mounting another filament support, having a filament receiving portion, with its portion in alignment with the said center and other portion, locating an anode on its lead adjacent the grid by the tool, securing the anode to its lead, removing the tool, and completing the device by sealing the sections together.

24. In the manufacture of an electron discharge device involving a vessel of precast sections, one provided with leads for a grid, an anode and fila-

ment supports, the method which comprises positioning a filament support with a filament receiving portion on its respective lead with the said portion located a given distance from the grid support, positioning a grid having a body formed for pivotal mounting on its lead and to support grid wire formed arcuately about a center, positioning a tool on the grid to move the grid thereby about its lead to align the center thereof with the portion, mounting another filament support, having a filament receiving portion, with its por-

tion in alignment with the said center and other portion, welding a filament to the filament supports at the portions thereof, moving the grid again through the aid of the tool to position the center thereof at the center of the filament should the filament have moved during welding, removing the tool, mounting an anode on its lead adjacent the grid, and completing the device by sealing the sections together.

10

CHARLES T. GODDARD.
